UNITED STATES PATENT OFFICE

131,059

DESIGN FOR A ROAST RACK

George C. Lynch, Los Angeles, Calif.

Application March 15, 1941, Serial No. 99,626

Term of patent 14 years

To all whom it may concern:

Be it known that I, George C. Lynch, a citizen of the United States, residing at Los Angeles, in the county of Los Angeles, and State of California, have invented a new, original, and ornamental Design for a Roast Rack, of which the following is a specification, reference being had to the accompanying drawing, forming part thereof.

Referring to the drawing:

Figure 1 is a perspective view of a roast rack, showing my new design; and

Figure 2 is an enlarged top plan view of the roast rack, in collapsed position.

The characteristic feature of my design resides in a roast rack of the type disclosed, having a base of the specific configuration shown.

I claim:

The ornamental design for a roast rack, as shown and described.

GEORGE C. LYNCH.
